UNITED STATES PATENT OFFICE.

LE GRAND TERRY, OF DUNDEE, NEW YORK.

DOOR-HANGER.

SPECIFICATION forming part of Letters Patent No. 256,929, dated April 25, 1882.

Application filed July 18, 1881. (No model.)

To all whom it may concern:

Be it known that I, LE GRAND TERRY, of Dundee, county of Yates, New York, have invented a new and useful Door-Hanger, of which 5 the following is a specification.

My invention relates to improvements in door-hangers made principally of wrought-iron and provided with rollers, with a peculiar track, support for the track, with devices by 10 which it is attached to the building, and a protection to keep the friction-rollers in place; also a hinge-joint in the hanger at or near the top of the door.

My invention consists of a door-hanger having a hinge-joint above the part attached to 15 the door to allow the lower end of the door to swing outward without injuring the hanger or track it moves on, in combination with a wrought-iron track or rail to support the hanger and a downward projection for the vertical 20 roller on the top of the hanger to pass behind to keep the horizontal wheel on the track. I attain these objects by the mechanism illustrated in the accompanying drawings, in 25 which—

Figure 1 is a front elevation as it appears when applied to a building and door for use; Fig. 2, a transverse vertical section of the several parts as they appear in practical operation; Fig. 3, the pivot for the supporting-roller 30 as it appears separate from the other parts.

Similar letters refer to similar parts in each view.

A is the rail or track for the supporting- 35 roller to roll or travel upon. It is made of a flat bar of iron any size or length required. It is placed with one edge up for the supporting-roller to roll upon. It is held in position by brackets or supports that have their ends 40 turned up, that project from the building, and have a hole through them to bolt or rivet the rails to them.

B is one of the brackets that hold the rail. It is made of wrought-iron and is shaped as 45 represented in Fig. 2. It has holes through the vertical part for bolts or screws to fasten it to the building, and a hole through the end that is turned up to bolt or rivet the rail to it.

Any number of these brackets may be used, 50 according to the size or weight of the door they support.

C is the hanger that holds the supporting-

roller, and its lower end is fastened to the door. It is made of wrought-iron and is shaped as shown in Figs. 1 and 2. The upper part is 55 bent inwardly above the supporting-roller, and the end bent up and fitted for the friction-roller a. The lower end has a hinge-joint made in it above the part attached to the door, which allows the lower end of the door to be moved 60 outwardly without breaking the hanger or injuring the rail or getting the roller off the track if an animal should get against the door. At the place where the center of the roller comes should be a hole. It is made through it for 65 the pivot to be put through; also holes for rivets or bolts to hold the pivot in place.

D is the pivot that holds the roller E in place. It is shaped as shown in Fig. 3. The round part on which the roller is placed is put 70 through the hanger and the outside part is riveted to it. The round end may have a nut on it; or it may be enlarged at the end to keep the roller on it.

E is the supporting-roller. It is made in 75 any ordinary manner, and must have the groove in it made to suit the edge of the rail.

F is the covering to shelter the other parts. A transverse section is shown in Fig. 2. It is fastened to the building, and the upper edge 80 may be varied to suit the covering of the building to which it is applied. The outward part has a downward projection extending to near the hanger and outward, so that the roller a may pass to and fro behind it. By means of 85 this the roller and hanger will not get out of their proper places.

What I claim as my invention, and desire to secure by Letters Patent, is—

1. The hanger C, having a hinge-joint between the door and rail, and having the roller a at its upper end and holes for the pivot D, 90 all as above specified.

2. The part F, having the downward projection, in combination with a hanger having 95 a horizontal wheel and vertical roller attached to a right-angled piece integral with the hanger-strap, as herein shown and described.

LE GRAND TERRY.
